OPHTHALMIC MOUNTING

Bert J. Lowres, East Orange, N. J.

Application April 11, 1940, Serial No. 329,042

2 Claims. (Cl. 88—47)

This invention relates to improvements in lens holding strap devices for ophthalmic mountings, and has reference, more particularly, to a novel lens strap device including a cushioning insert interposed between the same and a lens received and embraced thereby; this application being a continuation in part of my copending application Ser. No. 299,457, filed October 14, 1939.

This invention has for an object to provide a novel cushioning insert for engagement between a lens and the rigid attachment strap by which the same is coupled to the nose bridge, temples and similar parts which are included in a rimless ophthalmic mounting.

The invention has for a further object to provide a novel cushioning insert consisting of a unitary composite structure for application against the interior lens embracing surfaces of a lens strap device so as to be interposed between the same and a lens received and held therein; said composite structure comprising a thin, firm or non-flimsy backing plate or body, preferably made of sheet metal, of peripheral shape to correspond to the interior surface areas of the strap device, to a face surface of which backing plate or body is adhered a resilient facing body of soft rubber, preferably affixed to said backing plate by vulcanization.

Another object of this invention is to so interconnect and combine said strap device and said novel cushioning insert as to provide a unitary construction ready to receive a lens, thus simplifying the lens assembling operations which are required to be performed by retail distributors of ophthalmic mountings.

It has heretofore been attempted to interpose between the meeting surfaces of a strap device and lens assembly a thin sheet of rubber or like more or less resilient and flexible material. Although soft rubber is the most efficient cushioning medium, owing to the small and required irregular peripheral shape to which a thin sheet thereof must be reduced in order to fit within and properly correspond to the interior surface areas of a strap device with which it is to be used, as well as to its flimsy or limp character, considerable difficulty is experienced in handling and applying the same in use, especially by the retail optician. Furthermore, when a rubber facing is directly and permanently cemented to the interior surface areas of a strap device, considerable difficulty is encountered by the retail optician in manipulating and adjusting the strap device to lenses of varying thickness. Having in mind these objections, the novel cushioning in-

sert of this invention has been devised to overcome them, and to furnish a cushioning insert adapted to provide all the desirable cushioning characteristics inherent in soft rubber, and yet so supported by the included sheet metal backing that ease of handling, manipulation and fitting of the same both to the strap device and in interposed relation between the latter and a lens is assured. Furthermore, in order to facilitate and simplify the strap adjusting and lens assembling operations required to be performed by the retail optician, means are preferably provided for securing the cushioning insert in initial assembled relation to the strap device so as to provide a combination of these parts in a unitary construction, so arranged that the portions of the insert which face the interior sides of the strap arms are not attached thereto and consequently do not interfere or impede bending movements thereof during adjusting manipulation of the same by the retail optician.

An illustrative embodiment of this invention is shown in the accompanying drawing, in which—

Fig. 1 is a fragmentary front face view of an ophthalmic mounting showing an assembled strap device and lens equipped with a novel cushioning insert according to this invention; Fig. 2 is a perspective view of the novel cushioning insert per se; Fig. 3 is a longitudinal sectional view of a strap device with the novel cushioning insert, also shown in longitudinal section, opposed thereto ready to be operatively assembled therewith so as to combine therewith to provide a unitary construction, the parts being drawn on an enlarged scale; and Fig. 4 is also a longitudinal sectional view, further enlarged, showing unitarily combined strap device and cushioning insert operatively related to a lens adapted to be received and held thereby.

Similar characters of reference are employed in the above described views, to indicate corresponding parts.

Referring to the drawing, the reference character 10 indicates the lens and 11 the nose bridge of the mounting from which extends the lens embracing and holding strap device. Said strap device includes a butt portion 12 from which project the spaced outer and inner strap arms 13 and 14 between which the lens 10 is disposed so as to be embraced thereby. Said strap device further includes the upwardly and downwardly extending abutment lugs or members 15 and 16 which engage the peripheral edge of the lens 10, when embraced by the strap arms 13 and 14, to thereby hold said lens against rocking displace-

ment or play relative to a fastening screw 17 which passes through the outer strap arm 13 and lens 10 to screw into the inner strap arm 14.

The cushioning insert per se comprises a composite structure consisting of a thin but relatively firm backing body or plate 18, at least one face of which is covered throughout the area thereof with a facing layer 19 of soft, resilient material. Said backing body or plate 18 with its facing layer 19 is peripherally shaped to provide parts substantially corresponding to the shapes of the interior faces of the butt portion 12, strap arms 13 and 14 and abutment lugs 15 and 16 of the strap device.

In a practical embodiment of the novel cushioning insert, the backing body or plate 18 is made of sheet metal of a suitable kind, and preferably of a soft or annealed metal which may be easily bent angularly to conformingly dispose the parts thereof for contiguous facing relation to the interior surfaces of corresponding strap device parts, and so that the insert may be easily bent into the U-shape required to embrace the marginal portions of a lens of any given thickness. The facing layer of the insert is preferably made of soft vulcanized rubber, and is preferably adhered to the surface of the metallic backing body or plate 18 by direct vulcanization thereto, so as to become unitary therewith. The portions of the cushioning insert which correspond to and overlie the strap arms 13 and 14 are pierced to provide openings 20 to register with the fastening screw receiving opening of said strap arms and the lens embraced thereby. The composite cushioning insert need not be made thick and clumsy. It has been found that a very satisfactory insert is provided when the metallic backing body or plate 18 approximates $\frac{1}{1000}$ of an inch in thickness, and the rubber facing layer 19 approximates $\frac{1}{2000}$ of an inch in thickness.

It will be obvious that the backing body or plate 18 of the cushioning insert provides a relatively rigid or non-flimsy support for the mass of rubber facing 19, which nevertheless permits the easy bending of parts of the insert into and their subsequent retention in such angular relations as may be required to conform the same to desired overlying relation to different interior surfaces of the strap device and for opposition to the faces and edge of a lens inserted into the embrace of the strap device.

Owing to the support afforded by the sheet metal constituent of the insert, as well as the ease with which the latter may be angularly bent to conform the same to the interior of a strap device with which it is desired to be employed, the novel insert of this invention may be easily manipulated and inserted into a strap device by the retail optician either before or when assembling a lens 10 in secured relation to the strap device. It has been found, however, that the retail optician's work is further facilitated and minimized if the insert is initially combined with the strap device to form therewith a unitary construction. To this end this invention also provides novel means for so combining the insert and strap device. The means serving such purpose comprises the provision of a tubular metallic stud 21 having one end 22 imbedded and secured in the body of the butt portion 12 of the strap device, in such manner that its other end 23 projects from the inner face of said butt portion perpendicular to the plane of said face, and thus into the lens receiving space intermediate the arms of said strap device (see Fig. 3). The cushioning insert is angularly

bent into U-shape to conform to the lens receiving space intermediate the strap device arms, and so as to provide a back portion 24 (see Fig. 3) to abut the inner face of the strap device butt portion 12. In the back portion 24 thus formed is pierced an opening 25 through which the projecting end 23 of the stud 21 will outwardly extend, when the insert is moved into the embrace of the strap device (as shown by broken lines in Fig. 3). When the insert is thus disposed in assembled relation to the strap device, the projecting end 23 of the stud 21 is laterally upset, by application thereto of a suitable tool, so as to form an annular keeper flange 26 (see Fig. 4). As this keeper flange 26 is thus formed and flattened home, it will squeeze out the adjacent rubber mass of the insert facing 19 so as to firmly grip and anchor the underlying backing body or plate 18 against the strap device butt portion, and so as to imbed itself in said rubber mass of the facing 19 in countersunk relation thereto, whereby, when a lens 10 is introduced interiorly of the insert, the lens edge will be cushioned by such rubber mass and fended thereby from contact with the keeper flange 26 (see Fig. 4). By use of this arrangement, the insert may be furnished to the retail optician in initial combined relation to the strap device so as to form therewith a unitary construction. In such unitary construction, since the parts of the insert contiguous to the inner faces of the strap device arms 13 and 14 are not adhered or secured per se to said arms, the latter may be easily adjustingly bent, without impedance by the insert, to vary the spacing thereof for accommodation of lenses of varying thicknesses, and the contiguous insert arms likewise may be easily bent to conform to the adjusted disposition of the strap device arms.

When the cushioning insert is operatively interposed between a strap device and the lens embraced by the latter, the metallic backing body 18 is disposed contiguous to the interior surfaces of the parts of said strap device, while the rubber facing layer 19 is disposed against the lens surfaces. When thereafter the assembly is secured by screwing home the fastening screw 17, the latter may be driven home tightly, so that the strap device is firmly bound thereto, and yet the binding pressure will be equalized and distributed by the resilient or yielding cushioning facing 19 of the insert, so that risk of fracturing of the lens is avoided, while at the same time all looseness and undesirable play between the lens and strap device is likewise prevented by the presence of the interposed cushioning means.

Although in a preferred embodiment as above described, the body plate of the cushioning insert consists of a thin metallic member, nevertheless other firm or non-flimsy but bendable sheet material could be used for the purpose; and, likewise, although soft rubber is preferred for the resilient medium of the insert, other equally soft and resilient materials could be substituted therefor.

Having described my invention, I claim:

1. In an ophthalmic mounting, a strap device having a butt portion and laterally spaced arms angularly extending therefrom to receive a lens therebetween, a stud extending perpendicularly from the inner face plane of said butt portion intermediate the arms of said strap device, a cushioning insert comprising a composite structure consisting of a thin substantially rigid but bendable non-resilient backing plate and a facing layer of soft resiliently compressible material sup-

portedly adhered thereto, said insert being bent to conform to and overlie the inner surfaces of said strap device arms and so as to provide a back portion to lie contiguous to the inner face 5 of said strap device butt portion with the facing layer presented to oppose a lens received in said strap device, said back portion having an opening through which said stud extends, and the free end of said stud being upset to provide a lateral 10 keeper flange flattened home in holding relation to said insert and in countersunk imbedded relation to and below the surface of the facing layer of the latter whereby a firmly compressed portion thereof lies intermediate said flange and the 15 backing plate.

2. In an ophthalmic mounting, a strap device having a butt portion and laterally spaced arms angularly extending therefrom to receive a lens therebetween, a tubular stud imbedded in said 20 butt portion and having a free end portion extending perpendicularly from the inner face

plane of said butt portion intermediate said strap device arms, a cushioning insert comprising a composite structure consisting of a thin substantially rigid but bendable sheet metal backing plate and a coincidental layer of soft rubber vulcanized thereto, said insert being bent to conform to and freely overlie the inner surfaces of said strap device arms and so as to provide a back portion to lie contiguous to the inner face of said strap device butt portion with the rubber layer presented to oppose a lens received in said strap device, said back portion having an opening through which said stud extends, and the walls of the thus extending stud being upset to provide a lateral keeper flange flattened 15 home in holding relation to and below the surface of said insert and in countersunk imbedded relation to the rubber layer of the latter, whereby a firmly compressed portion thereof lies intermediate said flange and the backing plate. 20
